(57) **CLAIM**

The ornamental design for a satchel, as shown and described.

DESCRIPTION

FIG. 1 is a perspective view of a satchel showing my new design.

FIG. 2 is a front view of a satchel.

FIG. 3 is a rear view of a satchel.

FIG. 4 is a left side view of a satchel.

FIG. 5 is a right side view of a satchel.

FIG. 6 is a top view of a satchel.

FIG. 7 is a bottom view of a satchel; and,

FIG. 8 is a perspective view of a satchel, showing the state of strap pulled out.

Any shading and cross-hatching are not features of the design but are utilized to illustrate the surface contours of the satchel design in the drawings.

The broken lines in the drawings depict portions of the satchel that form no part of the claimed design.
